BULLDOZER TOOTH

Joseph Clyde Murphy, Frannie, Wyo., assignor of
one-half to Paul Weaver, Frannie, Wyo.

Application February 7, 1945, Serial No. 576,517

2 Claims. (262-8)

The present invention relates generally to that class of grading machines known as bulldozers and more particularly to an improved bulldozer tooth.

One of the principal objects of the invention is to provide a bulldozer tooth which may be quickly attached to any bulldozer blade and moldboard for the purpose of breaking shale, rock, frost or other material too hard for a conventional bulldozer blade to penetrate.

Another object of the invention resides in the provision of a device of this character which is readily adjustable on the bulldozer blade and moldboard, which may be used without injury to said blade and moldboard, and which may be conveniently carried on the frame of the bulldozer for immediate use, thus eliminating the need for heavy trailing equipment.

A further object of the invention is to provide a bulldozer tooth which is simple in construction, highly efficient in use, and which may be manufactured in quantity at low unit cost.

Other objects of the invention, not specifically mentioned hereinabove, will become apparent as the description proceeds.

In the drawings forming a part of my application:

Figure 1 is a front elevation of a bulldozer moldboard and blade equipped with a pair of the teeth forming the subject matter of my invention, said teeth being shown in dotted lines in alternate positions.

Figure 2 is an enlarged detail plan view showing the adjustable mounting for the upper end of the tooth.

Figure 3 is a side elevation of my invention in proper position on the moldboard and blade.

Figure 4 is a perspective view of the invention.

Referring now more particularly to the drawings, wherein similar reference numerals will be used to designate like parts, the numeral 1 indicates generally a bulldozer moldboard which is of conventional construction and which is provided at its lower edge with a hardened steel blade 2. The moldboard shown is of arcuate cross-section.

The improved bulldozer tooth forming the subject matter of my invention is indicated generally at 3 and includes an arcuate elongated body 4 which terminates at its lower end in a forwardly curved point 5. The rear edge of the lower end portion of the body terminates in a heel 6, and directly above said heel said body is notched to define a recess 1. As best seen in Figure 3, the upper and lower walls of the recess are shaped 55

conveniently to receive the upper and lower edges of the blade 2 so that said blade will effectively retain the lower end of the tooth in proper operative position on the moldboard.

Within the recess 1 the body is notched, as at 8, to receive a brace 9 which extends transversely at each side of said body and tends to prevent rocking of the tooth on the moldboard 1. Similarly, the rear edge of the body 4 is notched medially of its length, as shown at 10, to receive a brace 11 which provides further bracing against rocking movement of the tooth.

As best seen in Figure 4 of the drawings, the upper end portion of the body 4 is reduced and fashioned to define a straight shank 12 substantially square in cross-section. The shank 12 normally extends through an elongated slot 13 in a clamping plate 14 which, as shown in Figures 2 and 3, adjustably mounts the tooth on the moldboard. More specifically, the clamping plate 14 is formed with a depending lip 15 which is undercut obliquely, as at 16, to engage the rear edge of the moldboard 1. A set screw 17 is threaded through an opening, which communicates between the forward end of the plate 14 and the slot 13, so that its inner end engages the front face of the shank 12. Tightening of the set screw will urge the body 4 into tight engagement with the moldboard 1 so that the tooth 3 will be limited against accidental displacement. A lock nut 18 is carried on the screw 17 and is tightened for securing said screw in an adjusted position.

In Figure 1, I have shown two of my bulldozer teeth in position on a moldboard. It should be understood, however, that as many teeth as desired may be used. The teeth may be moved to different positions on the moldboard 1, or removed entirely therefrom, by simply loosening the screw 40 17 for relieving pressure on the shank 12.

My improved bulldozer tooth has proven particularly effective for digging close to vertical banks, which operation cannot be accomplished by trailing rooters. Moreover, the invention has proven highly successful when used for breaking shale, frost, rock, hardpan and other substances too hard for an ordinary bulldozer blade to penetrate.

It should be understood that various modifications may be made in the invention without departing from the spirit thereof. For example, the body 1 will have to be made in different sizes and slightly different shapes to conform to different makes and sizes of bulldozers.

Having described the invention, I claim:

1. A bulldozer tooth including a curved body terminating at its lower end in a forwardly disposed downwardly inclined point and at its upper end in a reduced squared shank, said body having a recess in its rear wall to receive a bulldozer blade and said recess being formed with a notch, a brace in the notch for bracing the tooth against rocking movement on a bulldozer moldboard, and a clamping plate engageable with

the shank for mounting the tooth on a bulldozer moldboard.

2. As a new article of manufacture, a bulldozer tooth comprising an elongated arcuate body terminating at one end in a sharpened point, said body being formed at its upper end with a reduced squared shank and with a recess medially of the length of its rear wall, and a brace carried in the recess.

JOSEPH CLYDE MURPHY.
